UNITED STATES PATENT OFFICE.

HAROLD SCOTT HEWITT, OF BRANTFORD, ONTARIO, CANADA.

DESIGN FOR AN ORNAMENT FOR RADIATORS OF MOTOR CARS.

Application filed February 29, 1928. Serial No. 25,622. Term of patent 3½ years.

To all whom it may concern:

Be it known that I, HAROLD S. HEWITT, a subject of the King of Great Britain, residing at the city of Brantford, in the county of Brant, Province of Ontario, Canada, have invented a new, original, and ornamental Design for an Ornament for Radiators of Motor Cars. of which the following is a specification, reference being had to the accompanying drawings, forming part thereof, in which—

Fig. 1 is a side elevation of an ornament for radiators of motor cars, showing my new design; and

Fig. 2 a plan view.

I claim:

The ornamental design for an ornament for radiators of motor cars, as shown.

HAROLD SCOTT HEWITT.
